UNITED STATES PATENT OFFICE

ARTHUR E. BLASHILL, OF MONTREAL, QUEBEC, CANADA

MECHANISM FOR SUPPLYING LENGTHS OF WIRE

Application filed November 4, 1926, Serial No. 146,215. Renewed September 13, 1929.

My invention relates broadly to supplying definite lengths of wire for any purpose and, although it is particularly adapted for use in conjunction with machines for manufacturing wire fabric, especially machines of the high speed type for manufacturing wire fence and the like, it is to be distinctly understood that it is not confined thereto but may be utilized to advantage with any machine requiring wire to be supplied to it in successive definite lengths.

The primary object of the invention is to provide a combined means for continuously feeding a length of wire longitudinally and for cutting the wire into uniform lengths without stopping or varying the speed of the feeding movement of the wire.

A further object is to provide feeding means which is synchronized with the mechanism of another machine and adapted to successively deliver the cut lengths thereto in such manner as to provide brief intervals between said deliveries.

A further object is to provide means which will function in the above manner at a high speed with great precision and which may be easily and quickly adjusted for the purpose of varying the longitudinal measurement of the cut lengths of wire.

To this end the invention consists of the combination, construction and particular arrangement of the parts hereinafter described and illustrated in the accompanying drawings, in which

Figure 1 is a side elevation of a high speed precision wire feeding and cutting machine constructed according to my invention;

Figure 2 is a plan view thereof;

Figure 3 is an end elevation of the main feeding and cutting apparatus;

Figure 4 is a vertical sectional view taken on line 4—4 Figure 1;

Figure 5 is a detail view of the flying cutter and means for actuating the same.

Figure 6 is a detail fragmentary sectional view of the chain loops showing the flying cutters in cutting position;

Figure 7 is a plan view of one of the chain loops illustrated in Figure 6; and

Figure 8 is a detail sectional view taken on line 8—8 Figure 4.

The accompanying drawings illustrate the preferred embodiment of my invention for successively delivering uniform lengths of stay wire to the fabric forming mechanism proper of a high speed machine for manufacturing wire fence. Such fabricating mechanism locks the stay wires upon the strand wires at their points of intersection and as its specific construction has no bearing upon the present invention it is shown in outline only.

Referring to Figure 1 the fabric forming mechanism is indicated at A, the main stay wire feeding and cutting means at B, and the auxiliary means for feeding the cut lengths to the fabric forming mechanism, at C.

In high speed fence machines to which the present embodiment is particularly adapted, the strand wires are fed intermittently in an upward direction and the stay wires are fed to positions extending at right angles to the strand wires, and a stay wire is locked upon the strand wires during each interval of rest of the latter. It is necessary, therefore, that the means for feeding the stay wires be synchronized with the means for feeding the strand wires and the lock forming means.

To accomplish this, a very rapid feeding and cutting of the stay wires is necessary owing to the fact that they must travel a distance substantially equal to their own length for each intermittent movement of the strand wires. It is obvious, therefore, that

loss of time due to the cutting of the stay wires to the required length, must be avoided. At the same time, it is essential that the stay wires be precisely measured before they are cut to ensure that the exact amount of

wire be provided for wrapping or twisting around the marginal wires of the fence. This desideratum is obtained by the embodiment of my invention which I will now describe in detail.

The main feeding mechanism is supported in a frame 2 which is adjustable upon a base 3 in the direction of the feed of the stay wire to and from the auxiliary feeding means for a purpose which will be presently described.

This main feeding mechanism consists of two endless sprocket chains 4 and 5, arranged one above the other with the bottom side 6 of the top chain extending in close proximity to the top side 7 of the bottom chain, two sides 5 coacting to frictionally grip and feed the stay wire.

The top chain passes around a pair of sprocket wheels 8, 9, and the bottom chain around a pair of corresponding sprocket wheels 10 and 11, the wheels 8 and 10 being keyed upon shafts 12 and 13, respectively located in fixed positions at one end of the frame 2, and the wheels 9 and 11 rotating freely upon shafts 14 and 15, located at the opposite end of the frame and adjustably mounted in slots 16 and 17, the last mentioned shafts being secured in their adjusted positions by a nut 18 screwed onto the reduced threaded end 19 of each shaft. The chains may be driven in unison from any convenient source of power. In the illustrated embodiment they are driven from the auxiliary feeding means, to be presently described, through sprocket chain 20, sprocket wheel 21 keyed on shaft 12 and intermeshing gears 22 and 23 keyed on shafts 12 and 13 respectively.

The chains consist of a series of links flexibly connected together with their ends overlapping and each link has a longitudinally grooved periphery 24 to accommodate the wire to be fed.

Each link is substantially U-shape in end elevation, and comprises vertical sides 25 and 26 united by a transverse back portion 27 formed integrally therewith, the back portion having a flat peripheral surface 28 with a longitudinal groove 29 therein, which is aligned with the grooves in the other links, thus unitedly presenting one substantially continuous groove when in wire gripping position. The links are flexibly connected together by pins 30 passed transversely through the overlapping link ends, the pins carrying rollers 31, which intermesh with the teeth of the sprocket wheels.

In addition to acting as anti-friction members between the pins and the teeth of the sprocket wheels, the rollers 31 also coact with means for causing the links, as they move through the active feeding zone, to press tightly against and frictionally grip the wire. This means consists of two presser plates, indicated at 32 and 33 respectively, one being fixed and the other being movable relatively thereto. The fixed plate 32 is mounted upon the main frame 2 in position beneath the top side or wire engaging portion of the bottom chain and in bearing relation with the rollers thereof, as indicated in Figure 1.

The movable plate 33 is mounted upon the eccentric ends, 34 and 35, of a pair of shafts, 36 and 37, rotatable in the frame, and is

caused to press downwardly upon the rollers of the wire engaging portion of the top chain by yielding means, consisting of arms 38 and 39 keyed upon the shafts 36 and 37, respectively, in positions extending towards each other, a bolt 40 extending through openings in the free ends of the arms, and a spring 41 encircling the bolt and bearing between a nut 42 on the upper end of the bolt and the uppermost arm 39. This construction and arrangement of parts imparts to the eccentric portions 34 and 35 a tendency to move in a downward direction and consequently to exert a downward pressure, through the plate 33, on the bottom side of the top chain. The downward pressure of the top plate may be varied by adjustment of the nut 42.

From the foregoing it will be seen that, when the chains are driven by their sprocket wheels, the stay wire will be continuously fed horizontally from left to right towards the auxiliary feeding means at a speed equal to the peripheral speed of the chains.

As hereinbefore pointed out, one of the principal objects of the present invention is to cut the stay wire while it is in motion. This is accomplished by a flying cutter carried by each chain and movable therewith, the cutters being indicated at 60 and 61, respectively, and coacting with each other to cut the wire.

The shank of each cutter is constructed in the form of a block 61^a vertically slidable in an opening 62 in the back of one of the links of each chain, and having its outer end terminating in a cutting blade 63, movement of the block both inwardly and outwardly being limited by a cotter pin 64, extending transversely through the link and entering a notch 65 in the adjacent side of the block. The cutters, which are located directly opposite each other, are automatically propelled outwardly to a position to sever the stay wire, when they reach the end of their travel through the actual wire feeding zone. This is effected by the teeth of sprocket wheels 8 and 10 which mesh with the cutter links at this point, the dimensions of the teeth and cutters being such that the outer ends of the former engage the inner ends of the latter and push the cutters outwardly, as indicated in Figure 6.

It will be noted that the wheels 9 and 11 are set far enough apart to permit the passage of the cutters without causing the latter to act on the wire.

This construction and arrangement of parts measures the length of the stay wire with great accuracy and makes it possible to continuously feed the wire at a very rapid speed without affecting the cutting operation.

The auxiliary feeding means is so located, relatively to the chain feeding mechanism, that it receives the end of each stay wire

length just before the latter is cut, so that, when the cut is effected, the feed will be continued by the auxiliary means. This auxiliary means consists of a pair of feed rolls 50 and 51, which in the present embodiment have a fifty per cent (50%) greater circumferential speed than the speed of the sprocket wheels 8 and 10 and than the linear speed of the chains and which are driven synchronously with the fabricating mechanism proper, so that the delivery of the stay wire lengths to the latter will be correctly timed with the intermittent feed of the strand wires and the operation of the mechanism for locking the stay wire upon the strand wires. The feed rolls 50 and 51 are keyed upon the ends of shafts 52 and 53 which, in turn, are supported in the frame 2^a and carry intermeshing gears 54 and 55 at their opposite ends. The shafts 52 also carry a sprocket wheel 56, which intermeshes with the sprocket chain 20 for driving the main feed, and any suitable means 58 for operative connection with the main drive of the machine.

25 The wire may be cut into any desired lengths within reasonable limits by simply increasing or decreasing the length of each of the feeding chains and by adjusting the distances between their sprocket wheels accordingly, and between the main feeding unit and the auxiliary feeding unit, the last-mentioned distance being slightly less than each stay wire length.

Operation

35 Briefly stated the operation of the machine referred to in the foregoing description is as follows:

With the cutters at the end of their horizontal travel from left to right and the end of the stay wire inserted between the chains at the left, the parts are set in motion. The chains at once pull the wire along between them and feed it into position between the auxiliary feed rolls, which have a 50% greater feeding speed than the chains. Immediately after the wire is gripped by the feed rolls, it is severed by the cutters and the severed length is rapidly propelled to position extending across the strand wires, the slower speed of the main feed providing the necessary interval required to lock the preceding stay wire upon the strand wires before the succeeding length is delivered.

55 From the foregoing it will be seen that the feeding operation may be carried on at a very high speed and that the wire is measured and cut into uniform lengths with great precision, the cutting operation being in no way affected by the high speed of the feed.

What I claim is as follows:

1. In a machine of the class described, the combination of wire feeding means, consisting of a superposed pair of endless chains,

the adjacent plies of which are adapted to frictionally grip the wire between them, means for driving said chains in unison, and wire cutting means forming a component part of said chains, said cutting means being constructed and arranged to be actuated at the point of exit of the wire from the chains. 70

2. In a machine of the class described, the combination of wire feeding means, consisting of a pair of endless chains, the adjacent plies of which are adapted to frictionally grip the wire between them, adjustable means for yieldingly pressing said plies upon the wire, means for driving said chains in unison, and wire cutting means forming a 80 component part of the chains and arranged to operate to cut the wire as it issues from between the chains.

3. In a machine of the class described, wire feeding means consisting of a pair of 85 endless chains, the adjacent plies of which engage the wire, means to drive said chains in unison, wire cutting means carried by the chains, and auxiliary feeding means engaging the end of each length of wire immediately 90 before it is cut, said rolls being actuated at a higher speed than said chains.

4. In a machine of the class described, combined wire feeding and cutting means, consisting of a pair of endless chains adapted 95 to grip the wire between them, sprocket wheels for said chains, and cutters carried by the chains and adapted to be directly actuated by the teeth of said sprocket wheels.

5. In a machine of the class described, 100 wire feeding means consisting of a pair of endless chains adapted to coat to frictionally grip and feed a wire, the links of said chains having wire-receiving grooves, pins flexibly connecting the links, rollers on said 105 pins, and means for exerting pressure upon the wire-gripping portions of the chains, comprising a fixed member adapted to engage the rollers of one of the chains, a movable member adapted to engage the rollers of 110 the other chain, and springs to press said movable member towards said adjacent rollers.

6. In a machine of the class described, a chain for feeding a length of wire, a flying 115 cutter carried by one of the links of said chain and adapted to cut the wire during its feeding movement, said cutter being slidable within its carrying link in a direction transverse to the wire, and a sprocket wheel 120 intermeshing with the chain and adapted to actuate said cutter.

7. In a machine of the class described, combined wire feeding and cutting means, consisting of a pair of endless chains engaging 125 the wire between them, flying cutters carried by said chains, means for driving said chains in unison and for actuating said cutters.

8. In a machine of the class described, 130

combined means for continuously feeding a wire at a constant speed and for cutting the wire into uniform lengths while it is being so fed, said means consisting of a pair of endless chains engaging the wire between them and cutters carried by said chains, auxiliary feeding means adapted to engage each length of wire before it is cut off and to convey it away, after it has been cut off, at a higher speed than said chains the latter being constructed and arranged to release each cut length of wire simultaneously with the cutting off of said length.

9. In a machine of the class described, wire feeding means consisting of a pair of coacting parallel members traveling longitudinally in unison with each other and adapted to grip the wire between them, means for yieldingly pressing said members together, said means consisting of a fixed presser plate bearing against the outer side of one of said members, a movable presser plate bearing against the outer side of the other of said members, opposed eccentrics carrying said movable plate, and resilient means operatively connected to said eccentrics to cause the movable plate to exert pressure upon its wire feeding member.

10. Mechanism for delivering cut lengths of wire successively to a wire-working machine, comprising a pair of endless chains adapted to grip a wire between them, sprocket wheels supporting and driving said chains, a cutter carried by one link of each chain, said cutters being constructed and arranged to be actuated by the teeth of certain of said sprocket wheels, means to drive said wheels and chains at a constant speed, auxiliary feeding means located between the end of said chains and the machine to be supplied, said auxiliary being driven at a higher speed than said chains and being adapted to engage the end of the wire just before it is cut, and means to yieldingly press together the portions of the chains which grip the wire.

Signed at the city of Montreal, Province of Quebec, this 22nd day of October, 1926.

ARTHUR E. BLASHILL.
